UNITED STATES PATENT OFFICE.

ANDREW ARCHER, OF WEST RUTLAND, MASSACHUSETTS, ASSIGNOR OF ONE-HALF TO
KEARNS J. WHALEN, OF WEST RUTLAND, MASSACHUSETTS.

LOOM-SHUTTLE.

1,300,102.

Specification of Letters Patent.

Patented Apr. 8, 1919.

Application filed September 22, 1916. Serial No. 121,674.

To all whom it may concern:

Be it known that I, ANDREW ARCHER, a citizen of the United States, residing at West Rutland, in the county of Worcester and State of Massachusetts, have invented a new and useful Loom-Shuttle, of which the following is a specification.

This invention relates to a loom shuttle, and more particularly to a detachable bobbin 10 spindle for use in such shuttles. This type of shuttle and spindle is largely used in the weaving of worsted goods, and the yarn for such goods is often spun in outside or independent mills. The transportation and increased handling of the bobbins thus incurred causes a large amount of breakage of the bobbins, particularly in the thin barrel portion thereof. After the bobbins have been cracked or broken it is difficult to weave 20 off the yarn thereon without excessive yarn breakage when using the common type of spindle which has merely a small button or head to keep the bobbin in place. This worsted yarn is frequently very valuable 25 and the waste of any portion thereof must be avoided.

It is the object of my invention to improve the construction of spindles of the type above described, rendering them more durable and efficient in operation without substantially increasing the cost of manufacture thereof.

With this object in view, one feature of my invention relates to the provision of a 35 head for the bobbin spindle which is substantially larger in diameter than the barrel of the bobbin and in which also the yarn-engaging surface is peculiarly adapted to increase the so-called "throw" of the yarn 40 away from the tip of the bobbin.

Another feature of my invention relates to the provision of a spindle head of sufficient weight so that the spindle cannot be easily displaced upwardly by the movement of the 45 shuttle, and also of sufficient strength to withstand injury if accidentally displaced.

A third feature of my invention relates to the provision of an improved construction of spindle head by which the tip of the bobbin 50 is more effectively centered and held in position. Other features of my invention relate to certain arrangements and combinations of parts which will be hereinafter de-

scribed and more particularly pointed out in the appended claim.

55

A preferred form of my invention is shown in the drawings in which—

Figure 1 is a top plan view of a shuttle with my improved spindle mounted therein,

Fig. 2 is an enlarged plan view of the 60 spindle and bobbin, and

Fig. 3 is a bottom plan view of the spindle shown in Fig. 2.

The shuttle 10 and bobbin 11 are of the usual construction and the yarn Y is led 65 from the bobbin past a friction 12 and through an eye 13 as is customary. The bobbin spindle comprises a shaft 14 provided with notches 15 and 16 and adapted to be inserted in a socket in the rear end of the 70 shuttle. When moved to horizontal position in the shuttle it is yieldingly held in this position by a spring 17, the notches 15 and 16 engaging pins in the shuttle provided therefor.

75

The novel features of my invention are found in the spindle head 20 which may be secured to the shaft 14 in any convenient manner, as by forcing or screwing the same on to the end of the shaft. Referring to 80 Figs. 1 and 2 it will be seen that the head 20 is of substantially larger diameter than the barrel of the bobbin 11. Furthermore the yarn-engaging portion of the head is formed as a cylinder of substantial length, which 85 formation of the head is found by experiment to substantially increase the "throw" of the yarn away from the tip of the bobbin as it is woven off. A typical broken bobbin is shown in Fig. 2, and the great utility of 90 this feature of my invention will be evident by reference thereto.

The spindle head 20 is also provided with an elongated and gradually tapered portion or extension for engaging and supporting 95 the tip of the bobbin. It is found that these bobbins vary somewhat in internal diameter and also that they weave off much better when firmly supported. By the use of the tapering extension of the spindle head each 100 bobbin may be firmly supported even though considerable variation occurs.

The head 20 is formed of metal, preferably steel, and is of substantial weight. In the running of the shuttles in a drop-box loom, 105 the boxes are sometimes out of alinement

with the shuttle race when the shuttle enters a box, and the shuttle is thus given an upward movement or jump which tends to swing the bobbin and spindle upward to engage the top of the shuttle box. This action frequently causes considerable damage to the spindles and also to the bobbins, when the common type of spindle with the small head is in use.

10 The head 20 possesses two important advantages when used under these conditions. In the first place, the substantial weight of the head assists the spring 17 in holding the spindle in place and less displacement of the 15 spindle and bobbin occurs. Furthermore the shape and solid construction of the head 20 enables it to withstand injury even when it receives a blow which would ruin the ordinary type of spindle. If the head 20 is 20 slightly dented or roughened by such engagement, the head contains sufficient material so that the roughened parts may be easily smoothed off.

While I have particularly described the 25 advantages obtained by the use of my improved spindle in connection with cracked

or broken bobbins, it is also of great utility with any bobbin in which the tip or barrel is in any way roughened or defective.

Having thus described my invention it 30 will be evident that changes and modifications may be made therein by those skilled in the art without departing from the spirit and scope of my invention as set forth in the claim, and I do not wish to be otherwise 35 limited to the details herein disclosed, but what I claim is:—

In a loom shuttle, a detachable bobbin spindle comprising a shaft and a solid metal head fixed to said shaft, said head having a 40 tapered bobbin centering portion and a cylindrical end portion of substantially greater diameter than the bobbin with which it is designed for use and of substantial length whereby the throw of the yarn is increased, 45 and being also of material weight relatively to said bobbin, whereby accidental upward displacement of the spindle and bobbin is prevented.

In testimony whereof I have hereunto 50 affixed my signature.

ANDREW ARCHER.
